UNITED STATES PATENT OFFICE.

FRANK C. MARQUARDT, OF BROOKLYN, NEW YORK, ASSIGNOR TO AMERICAN BANK NOTE COMPANY, OF NEW YORK, N. Y., A CORPORATION OF NEW YORK.

PROOF PRESS FOR MULTICOLOR WORK.

Application filed February 20, 1923. Serial No. 620,171.

My invention relates to a proof press for multicolor work, and more particularly to a proof press by which trial impressions in a plurality of different colors may be made under conditions which will approximate working conditions in a multicolor printing machine.

In multicolor work, it has been the common practice to ink the plates for each color separately and pull proofs from each plate entirely independent of every other plate and thereafter to pull proofs showing progressively the effects which will be secured as succeeding impressions in a predetermined order are made upon the printing machines. In this way proofs are secured which not only show impressions from the different plates in their distinctive colors, but impressions showing the progressive development of a complete reproduction including the combined cumulative impressions of the first plate with all succeeding plates, so as to show composite imprints after each impression is made from these plates, in the printing machine. Such proofs were pulled by means of an ordinary bed or galley bed adapted to receive the printing plate, usually a halftone plate, and an impression cylinder provided with the usual felt blanket, and having flanged wheels moving on tracks upon opposite sides of the bed, although under some conditions the old screw platen and bed press was used for this purpose.

A proof press embodying my invention is so constructed that a sequence of plates each representing a portion of a completed design, may be inked in one or more colors as desired, and a single proof pulled with one operation from all of said plates, the resulting impression being in a plurality of different colors.

The construction of the machine is such that if desired a separate proof may be pulled from each plate, or of any desired grouping of plates, to facilitate the make-ready of the press upon which plates corresponding with those of which proofs are being made are to be used, as well as to segregate the design of each plate to facilitate the production of photo-engraved plates for use upon the printing machines. Furthermore, proofs may be pulled from a plate or plates representing only a fragmentary part

to be incorporated in a complete design, to facilitate the making or building up of such completed design.

A proof press embodying my invention is so constructed that a planographic offset printing cylinder is brought successively into the operative relation to the plate upon a sequence of plate holders spaced apart a distance coinciding with the periphery of the printing cylinder or a multiple thereof so that as said cylinder passes the plate upon each holder, the ink design upon each plate will be transferred to within the same area upon the printing cylinder, the lines of the design upon one plate being in register with those upon another plate, and the impression being made upon a sheet of paper carried by an impression platen with which the printing cylinder co-operates after it has received the inked design from the plate or plates.

The proof press of my invention is particularly designed for use in connection with the production of safety tints, or safety line designs, in bank notes or similar instruments requiring a security print thereon, such tints ordinarily being light impressions with special inks so that but a single inking of the plate is required.

The press of my invention is so constructed that the printing cylinder is normally maintained above the plane of the impression platen and of the plates upon the various plate holders, during the movement of the carriage carrying same in one direction, (this carriage having reciprocatory movement) the printing cylinder being lowered automatically so as to cause each plate to transfer its portion of the design in ink to the printing cylinder upon its movement in the opposite direction towards the impression platen.

In order to secure identical timing during the inking of the printing cylinder by each of the plates, I reciprocate said cylinder by power at a uniform speed at all times, providing an automatically acting reversing mechanism for controlling the power for actuating same.

Primarily the purpose of the press of my invention is for laying out, or determining, an arbitrary color scheme, the inking being done by hand and the plate holders being so

constructed that with an inking roller of a certain width, a stripe of ink may be applied obliquely to the center line of the plate at a definite angle so that the other plate 10 holders may be set at a corresponding angle to permit the matching of colors in different plates. This condition is due to the fact that different colors may be, and ordinarily are, used upon the same plates, the work in connection with which the press of my invention is used not involving plates each having their own distinctive color as in ordinary multicolor work, nor color effects secured by the blending or overlaying of inks 15 of different colors. Each plate used upon a press of my invention represents merely a part of a design entirely independent of the colors which may be used, or the area covered by any particular color, such matters being entirely under the control of the operator of the proof press.

Since capacity is no factor in a press of this character, and since the preparation of the plates including inking is a hand operation, 20 power is required only when the printing cylinder is to be actuated. To meet this condition, I provide a controller mechanism which is readily accessible to the operator of the press at every point at which the carriage carrying the printing cylinder may be brought to rest, so that while the controlling mechanism may be automatically actuated to reverse the direction of travel of the carriage carrying the printing cylinder, 25 the operative effect of this mechanism is always under the control of the operator so as to permit the starting, stopping and reversing of the carriage entirely independently of the automatic mechanism.

40 The above characteristics in the control of the machine, require the provision of means supplementing the automatic mechanism for bringing the printing cylinder into the operative relation to the printing plates and the impression platen by a hand control for imparting movement to the cylinder into and out of such operative relation, which mechanism may also be utilized for moving the cylinder away from the impression platen, after an impression has been made, so as to prevent possible offsetting upon said platen.

55 The invention consists primarily in a proof press for multicolor work embodying therein a bed having a sequence of plate holders adapted to receive printing plates, an impression platen, a reciprocating carriage, a printing cylinder having a planographic offset printing surface thereon mounted upon said carriage, means simultaneously imparting definite positive rotative movement to said cylinder, and lineal traverse to said carriage, whereby said cylinder is brought successively into the operative relation to the plates upon each of said

plate holders, and said impression platen, and means whereby said cylinder may be so set as to operatively engage plates upon said bed, and said impression platen, or to be held out of engaging relation therewith, said plate holders being so positioned with relation to each other, and said printing cylinder being of a diameter to cause the design, upon the different plates to be impressed in ink in registering relation upon said cylinder; and in such other novel features of construction and combination of parts as are hereinafter set forth and described, and more particularly pointed out in the claims hereto appended.

50 Referring to the drawings,

Fig. 1 is a side elevation of a proof press embodying my invention;

Fig. 2 is an end view thereof;

Fig. 3 is a cross-section through the printing cylinder and its carriage;

Fig. 4 is a plan view of the press broken away and condensed;

Fig. 5 is a sectional view illustrating the throw-off mechanism operative upon the cylinder; and

Fig. 6 and 7 are detailed enlarged views of one of the plate holders.

Like numerals refer to like parts throughout the several views.

55 In the embodiment of my invention shown in the drawings, I employ an elongated bed 12 adapted to have mounted thereon at equal distances one from the other, a sequence of plate holders A, the number of said plate holders corresponding with the number of cylinders to be used in the printing machine upon which the plates from which proofs are pulled, or plates made therefrom, are to be used. Ordinarily a four-cylinder printing machine is used for this work. While all of the cylinders are not used upon every job, I preferably employ four plate holders, although the construction of the proof press is such that any number of these may be used. Also carried by said bed at one end of the sequence of plate holders, is an impression platen 13.

60 Throughout the full length of the bed, upon opposite sides thereof, are tracks 14 and 15 along which a cylinder 16 having a planographic printing surface 17 is adapted to roll so as to be brought successively into the desired operative inking relation to plates upon the various plate holders A and the impression platen 13. The cylinder 16 is provided with circular end plates 18 and 19 co-operating with the tracks 14 and 15 respectively, and preferably formed integrally with said cylinder.

65 The cylinder 16 is carried by a hollow shaft 20 having reduced arbors 21 and 22 rotatably mounted in eccentric bushings 23 and 24 respectively, said bushings being provided for the purpose of permitting the au-

BEST AVAILABLE COPY

1,660,236

omatic or manual movement of the cylinder 16 toward and from the bed 12.

The shaft 20 is mounted upon a sleeve 25 mounted upon a tie rod 26, one end of which rod is screw-threaded, as shown, and engaged by a nut 27. By this construction a composite shaft is provided which may be so reinforced, as shown, as to provide the desired rigid bearing areas for a cored cylinder, while at the same time the cylinder may, through the shaft 20, be connected with the source of power for rotating same, or disconnected from such source of power to permit manual operation of the cylinder, when desired.

The eccentric bushings 23 and 24 are mounted in bearing blocks 28 slidably mounted in side plates 29 of the carriage 30, which carriage is movable longitudinally of the bed 12. Said blocks are supported by suitable springs 31, and are forced into the desired engaging relation with the plates upon the bed 12, by means of screws 32 carried by the side plates 29 and acting upon said blocks 28 and against the tension of the springs 31.

Carried by the bed 12 adjacent the tracks 14 and 15 respectively are racks 33 and 34 co-operating with which are gears 35 and 36 carried by the shaft 20 closely adjacent the end plates 18-19 of the cylinder 16, said gears being secured in relation to said shaft and said cylinder in any desired manner so as to impart a positive rotative movement to the cylinder at a uniform rate of traverse with the rotation of the shaft 20 and the cylinder 16 carried thereby. This construction is provided, because positive rotary movement of the cylinder is essential in order to secure proper register of the designs upon the different printing plates, which can only be secured by the positive uniform rotation of the cylinder, great exactitude being possible when rack tracks and toothed traction wheels are used.

The bed of the machine, upon opposite sides thereof, is provided with channels 37 adapted to receive rollers 38 which engage the top of the channels and prevent any lifting action of the carriage or of the cylinder 16 carried thereby as a result of the engagement of the blanket 17 with the plates or with the impression platen.

Idly mounted upon the sleeve 21 is a worm gear 39 adapted to be connected to said gear by means of a clutch 40 normally held in the set position by means of the rod 26 and the nut 27, the clutch member 40 being splined to said sleeve 21 and acted upon by a plate 41 carried by the rod 26. The gear 39 is in constant mesh with a travelling worm 42 slidably mounted upon a shaft 43 extending for the full length of the machine, said shaft being grooved, as shown at 44, for the purpose of receiving a spline

or feather 45 carried by the slidably worm 42.

Owing to the length of the shaft 43, I have found it desirable to provide a sequence of swinging yoke supports 46, which by engagement with said shaft at different portions of the length thereof, will prevent sagging of the shaft while not interfering in any way with the free reciprocatory movement of the worm 42. The lower ends of the supports 46 are counterweighted, as at 47, to ensure their return to normal position, with the yoke thereof in engaging relation with the shaft 43, after the worm 42 has in passing moved same from their normal operative position.

The shaft 43 is rotated in any desired manner, as by means of a pulley and belt mechanism 48 driven from the motor 49.

By using the sliding worm and worm wheel construction described, I am enabled to secure uniform angular speed of the cylinder 16 with the desired reduction in speed to secure a proper inking interval, as well as a proper impression interval, uniformity in the speed of traverse of the cylinder being a factor in securing register of different portions of the design carried by different plates upon the plate holders A.

Associated with the motor 49 is a reversible electrical controller 50, the stem of which has a gear 51 cooperating with a rack 52 carried by a sliding rod 53 extending for the full length of the machine. The carriage 30 has a yoke 54 straddling the rod 53 and adapted to engage adjustable collars 55 and 56, the former of which will impart movement to the rod 53 in one direction to actuate the controller in a manner to reverse the direction of drive of the motor 49, and the latter of which will impart movement to said rod in a manner to interrupt the circuit to the motor 49 and thus stop the carriage after an impression has been made. Since the rod 53 extends the entire length of the machine upon the side thereof where the operator stands, it is apparent that the controller 50 may be manually operated by means of said rod to arrest movement of the carriage at any point, or cause it to return to its normal position before it has completed its full reciprocatory movement. This construction is desirable when a proof from any number less than the full number of plates is desired and the working conditions do not justify readjustment of the collar 55.

It is apparent that where electrical power is not used upon the machine, other well known expedients having the same operative effect as the controller 50 may be employed, it being desirable to provide a driving mechanism for the carriage controlled by an automatically acting reversing and stop mechanisms, which controller, however,

may be manually actuated for starting, stopping and reversing the actuating mechanism.

I also provide means whereby when the clutch 40 is released, the cylinder 16 may be turned manually by means of intermediate gears 57 and 58 and in mesh with the actuating gears 35 and 36, one of which as the gear 58 is driven from a gear 59 actuated by means of a hand crank 60. The gears 57 and 58 are carried by a hollow shaft 61 extending from one side of the machine to adjacent the other side thereof, said shaft being rotatably mounted upon a shaft 13 62 which, as will more fully appear herein-after, also forms a part of a mechanism for actuating the eccentric bushings 23 and 24.

The shaft 62, adjacent the opposite ends thereof, is provided with crank arms 63 and 20 64 which are respectively connected by means of links 65 and 66 with the eccentric bushings 23 and 24. Said shaft 62 is mounted in the side frame 29 of the movable carriage and the end thereof upon the same side of the 25 machine as the controller rod 53, carries a gear 67 and an operating handle 68 so that said eccentrics may be manually actuated in either direction to bring the printing cylinder 16 into the operative relation to the 30 plates upon the various plate holders and to the impression platen, or move it out of such relation. In addition to this manual control for the eccentric bushings, or throw-off mechanism, I provide automatically acting 35 means operative upon said shaft 62 whereby said eccentrics will be automatically actuated to move the printing cylinder into the operative plane in relation to the plates upon the holders A and the impression platen 40 toward one end of the reciprocatory movement of the carriage 30, the manual actuation of the bushings for moving the cylinder out of this plane being entirely feasible 45 since it will require no movement of the operator from adjacent one end of the machine to adjacent the other end thereof, and since capacity output is not a factor in the 50 operation of the press.

Mounted upon the side of the carriage 30 is a crank fitting, one crank of which is provided with a segmental gear 69 in mesh with the gear 67 carried by the shaft 62, and the other crank 70 of which projects in the path of a tappet 71 carried by the spring-pressed 55 slide 72 mounted upon said carriage in suitable bearings, the end of said slide being so positioned as to engage a bumper 73 at one end of the machine in a position where it will engage the slide 72 toward the end of 60 the reciprocatory movement of the carriage in one direction, while allowing a sufficient period of engagement to impart the maximum movement to the slide to operate the eccentric bushings 23 and 24. Preferably 65 this bumper is a cushioned bumper to com-

pensate for any slight absence of precision in its set, and to relieve the jar of impact, although this latter function is not essential, particularly in view of the fact that the plunger itself is spring-pressed.

The impression platen 13 is preferably a mere flat rubber faced table of a height to develop the desired printing pressure between it and the blanket 17 upon the cylinder 16. The dimensions of this platen are 75 such as to receive a sheet of paper of the desired size, and its location is such that the printing cylinder will pass therefrom before coming to rest, to permit the removal of the sheet carrying the proof.

Each of the plate holders A is of the same construction as every other, the construction being such as to not only ensure an equal spacing of these holders from each other and from the platen 13, but to permit such adjustment as is necessary for accuracy in the positioning of the plate upon one holder with relation to that upon every other holder. Each plate holder is also so constructed as to guide the inking roller to ensure the 80 inking of the plate with stripes of ink, as determined by the length of the inking portion of the roller, means being provided whereby the portion of the holder carrying the plate and the guides for the inking roller 85 may be angularly adjusted with relation to each other, to permit the application of stripes of ink obliquely to the center line of the holder. The portion of the holder adapted to receive and support the plate is so constructed as to position the clamps operative upon the plate with accuracy, and at the same time permit their rectilineal adjustment longitudinally of the bed of the press, or laterally thereof for the purpose of securing register of the designs upon the different 90 plates.

In Figs. 6 and 7 of the drawings, I have illustrated the form of plate holder which I have found highly satisfactory in use. This 110 plate holder comprises a member 74 adapted to rest upon the bed 12 and having parallel raised tracks 75 and 76 adjacent opposite edges thereof. In this portion 74 is a circular opening adapted to receive a segmental 115 fitting 77 having a rectangular portion indicated at 78 adapted to receive a plurality of square blocks 79 and a second set of oblong blocks 80, which blocks are capable of being so nested as to form pockets having 120 slideways 81 therein in which clamps 82 are slidably mounted. Each of the clamps 82 is provided with an adjusting screw as 83. These clamps are arranged in pairs, to form 125 a rectangular space adapted to receive the plate within the edge engaging projections 84 upon the respective clamps.

Preferably the fitting 77 is secured in a fixed position upon the bed 12 by means of studs passing through the openings 85 and 130

entering corresponding openings in said bed.

Two pairs of said clamps engage the end edges of the plate adjacent the side edges thereof, the remaining pair of clamps engaging said side edges substantially centrally thereof. The adjusting screws 83 adjacent the rectangular portion 78 bear against the edge wall of this portion, locking bars 86-87 bearing respectively upon the adjusting screws of the clamps engaging one end edge of the plate, and the adjusting screw of the clamp engaging a side edge of the plate, being provided. These locking bars are spring-pressed into engagement with the edge of some of the blocks 79 and 80 and with said adjusting screws respectively, but are permitted to recede therefrom to facilitate the mounting of a plate in, or its removal from, the holder.

20 The segmental fitting 77 is provided with a center gauge mark shown at 88, the portion 74 being provided with gauge markings to facilitate the setting of the holder with a definite angle of obliquity of the tracks 75-76, thus permitting different plates to be inked with the same degree of obliquity. The detailed construction of the locking mechanism is immaterial to the present invention, it being merely necessary 25 that the spring pressure rigging operative upon the bars shall bear against the wall of the circular opening in the portion 74 and be formed in an arc so as to prevent displacement of these parts during circular movement of the member 74 in relation thereto.

20 The member 74 and the segmental member 77 are provided with registering openings by which these parts may be immovably keyed together by means of the pin 89.

40 The operation of the herein described mechanism is substantially as follows:—

In use, a proof press embodying my invention differs from proof presses heretofore used in that while in ordinary proof presses the purpose is to secure a specimen impression for determining accuracy in a plate and permit correction of any errors before the plate is used, the press of my invention is 45 designed to permit the determination of the color scheme of a completed impression, which scheme is arbitrarily determined by the operator of the machine, the lines of the plate being merely for determining the portion of the completed design which is to be thus inked. The completed proof is a design in many colors, the combined product of the plates used, of the manner of inking each plate, and of the functioning of the 50 machine in collecting impressions from the different plates upon a planographic printing cylinder from which the proof itself may be made by a single impression.

55 The plates in the different plate holders, may have the printing surfaces positioned

with regard to the lines of different plates or any one plate, or considerable areas of the design upon one plate may be deleted, the nonprinting space thus left serving to permit portions of the design corresponding with those deleted, appearing upon other plates, to permit the desired inking of the plates in inks of different colors in such portions. Furthermore, while the proofs pulled by means of a machine embodying 75 my invention will represent the completed design, these plates may not correspond with the plates as actually used on the printing machine, but will serve as a guide to assist in the preparation of such plates as are 80 used upon, and in the makeready of, the printing machine.

The above condition is due to the fact that while the plates, as used upon the proof press will produce but a single complete design, 85 the plates actually used upon the printing machine bear many reproductions of this same design, such plates being acid etched cameo aluminum or zinc sheets.

A proof press embodying my invention 90 embodies characteristics by which each plate may be accurately inked throughout any selected area, so that the inked areas of different plates will form complementary portions of a complete design; and means whereby the ink from the different plates will be combined upon a printing cylinder so as to permit the making by a single impression of an imprint in all of the colors used. The press is also capable of being so controlled 95 that an impression from any plate may be made entirely independently of the other plates, may be combined and produced so as to guide the operator of the printing machine for reproducing this design, in the 100 production of the plates used upon said printing machine, and in the makeready of the machine.

In a printing press for reproducing designs in connection with which the proof 110 press of my invention is employed, the maximum number of plates which may be used upon the machine is four, so that four plate holders A are provided in the proof press, although it is not essential that all of these 115 holders be used upon every job.

While the present invention does not involve the making of the original plates, it is necessary for a clear understanding of the invention, to point out that the production 120 of such plates involves the making of a complete design and the separation of this design into as many parts as there are to be plates, this separation involving the deletion of lines in the design for each plate, 125 which lines appear in the design for another plate or plates, or the deletion of different but complementary fragmentary portions of the design for each plate, which deleted portions are retained in another of the plates. 130

In this manner it is possible for closely adjacent lines as they appear in the completed design, to be in different colors and portions of the design in one color may be completely surrounded by other portions of the design in a different color or colors.

When such plates have been prepared they are mounted upon the respective plate holders A, and the lines upon the different plates 10 are brought into accurate register by means of the adjusting screws 83, the member 74 and the blocks 79 and 80 serving as a rigid support for the plates, the edges of the plate being engaged by the projections 84. The 15 rectangular portion 78 will ensure approximate accuracy in the positioning of the plate in the holder, the screws 83 merely effecting that minute adjustment which may be necessary to secure absolute accuracy of register 20 of the portions of the designs upon the different plates, one with the others. The locking bars 86 and 87 engage one clamp screw of each pair of clamps and permit the separation of these clamps to receive the plate 25 while ensuring accuracy in the closing of the clamps upon the plate and the proper holding of the plates when once in position upon the holder.

After the plates are properly positioned 30 upon the holders, an inking roller having flanged end wheels movable upon the tracks 75 and 76 is used to apply stripes of ink of the desired width and of the desired color to the plates, each stripe being of a width 35 less than the entire design, either as a result of limiting the area of the inking roller to which ink is applied, or using an inking roller having a surface area of a width corresponding with the desired width of stripe. 40 Each plate will be inked as many times as there are different colors to be used upon that plate, the arrangement of the printing lines upon the plate determining the color effects secured in the completed design, or 45 the portion of the plate which will be inked by this hand inking roller. The tracks 75 and 76 will ensure lineal application of the ink to a certain definite area upon the plate.

In some work it is desired to have a somewhat triangular portion of the impression in one color so as to avoid, in any completed impression, the effect of stripe inking, it being necessary when this practice is followed, to impart a definite angular adjustment of the 50 tracks 75 and 76 about the axis of the plate upon the holder so as to obliquely ink the plate. This method of inking will ordinarily necessitate a similar adjustment of one or more of the other plates, which may be readily accomplished since each plate is exactly centered upon the axis about which such angular adjustment must be made. The gauge lines upon the parts 74 and the center gauge 55 mark 88, permits exactly similar adjustment 60 of any two or more plates. When all of the

plates have been properly inked, the gauge mark 88 is used to accurately center each plate and the pin 89 used to lock the plate in this position.

While the plate is being inked, the carriage 30 will be adjacent the impression platen 13, with the eccentric bushings 23 and 24 so set as to hold the blanket 17 of the printing cylinder 16 out of engagement therewith.

After the plates have been properly inked, 75 the sliding rod 53 is manually moved by the operator to the right, Fig. 1, thus actuating the electrical controller 50 through the pinion 51 and rack 52 in a manner to apply power to the motor 49 and thus rotate the shaft 43 and with it the worm 42. With the rotation of said worm, power will be transmitted through the worm gear 39 to the shaft 20 carrying the spur gears 35 and 36 meshing with the racks 33 and 34 respectively causing a simultaneous rotary movement of the cylinder 16 and traverse thereof lengthwise of the bed 12. Said gears and said racks are utilized merely to impart the desired simultaneous angular and lineal 85 movement to the cylinder 16, and hence there is no necessity for absolute precision in the construction of the racks 33 and 34 and the gears 35 and 36, so far as the development of pressure between the blanket 17 90 and the various plates upon the holders A and the impression platen 13, is concerned. As the carriage moves longitudinally of the machine, the worm gear 39 will carry the worm 42 along the shaft 43 to which it is 100 splined, or otherwise slidably mounted.

The shaft 43, as heretofore described, is supported against sagging by the supports 46, which will be moved out of the path of the worm as a result of engagement between 105 these parts during the lineal traverse of the worm along the shaft, the weight 47 restoring each support to its engaging relation with the shaft immediately upon the passage of the worm. Said supports 46 are provided to avoid possible loss of mesh between the worm 42 and the worm wheel 39 as a result of sagging of said shaft 43.

Assuming that the proof being made is to include the inked design upon all four plates, 110 the operator permits the carriage 30 to travel for the entire length of the machine until the yoke 54, as a result of its engagement with the collar 55, actuates the sliding rod 53, and the rack and pinion mechanism 51 115 and 52 to cause the controller 50 to reverse the direction of drive of the motor 49 and of the shaft 43, thus initiating a return movement of the carriage 30 under the control of the same mechanisms used for moving it in 120 its reciprocal movement toward said collar 55. During this return movement, the printing cylinder 16 will also be turned in 125 the reverse direction.

As the carriage 30 approaches the limit 130

of its reciprocatory movement toward the collar 55, the spring-pressed slide 72 will engage the bumper 73, thus causing the tap-
pet 71 upon said slide to impart a rotary
movement through the crank 70, the segmen-
tal gear 69, the gear 67, the shaft 62, the
cranks 63 and 64, and links 65 and 66, to the
eccentric bushings 23 and 24 sufficient to
force the printing cylinder 16 downwardly
10 to an extent to bring the rubber blanket 17
thereon into a plane where it will, during
the return reciprocatory movement of the
carriage 30, successively engage and receive
an inked impression from the plates upon
15 the various holders A, and thereafter engage
a sheet of paper which has in the meanwhile
been placed upon the impression platen 13.

During the reciprocatory movement of the
carriage 18 toward the collar 55, the circu-
20 lar end plates 18 and 19 will be raised by the
eccentric bushings 23 and 24 slightly above
the tracks 14 and 15 and out of engaging
relation thereto, but during the return recip-
rocatory movement of said carriage, said end
25 plates will engage said tracks.

As the carriage 30 approaches the limit
of its return reciprocatory movement, the
yoke 54 thereon will engage the collar 56 and
30 impart sufficient return reciprocatory move-
ment to the rod 53 to actuate the controller
50 in a manner to interrupt the circuit to the
motor 49 and thus arrest further movement
35 of the carriage, but not until the cylinder 16
has entirely passed the platen 13 and thus
completed the making of the impression.

When the carriage has completed this
movement, the eccentric bushings 23 and 24
will remain so set as to engage the blanket
17 of the printing cylinder 16, with the im-
40 pression platen 13, so that preparatory to
the next actuation of the press, it is neces-
sary for the operator to actuate the lever
68 manually to impart such movement to the
eccentrics 23 and 24 as will raise the cylinder
45 out of engaging relation with said platen,
to avoid possible offsetting upon the platen,
and to permit the cylinder to pass over the
various plates out of engaging relation there-
with.

If it be desired to pull a proof from, but
one plate, or any number of plates less than
the full number of plates, the operator will
actuate the controller rod 53 and cause the
carriage to move into the necessary relation
50 to the plate from which the proof is pulled,
or the first plate of a group of such plates
from which a combined imprint is desired,
and when the carriage 30 has reached the de-
sired point, to use the controller rod 53 for
60 interrupting the circuit to the motor 49 so
as to stop the carriage. The hand lever 68
is then used to actuate the eccentric bushings
23 and 24 to lower the printing cylinder 16,
and the motor again started to move the car-
65 riage toward the impression platen 13. The

motor is stopped when the desired ink im-
pressions have been made upon the offset
blanket 17, and the eccentric bushings again
actuated to raise the cylinder 16 so that it
will pass over the plates from which no im-
pression is desired, the motor being again
10 stopped before said cylinder reaches the im-
pression platen, so as to permit the lowering
of the cylinder so as to make the imprint.

The above practices are followed when all
of the plates are positioned in the holders A
upon the bed 12. If only one plate, or a
group of plates from which the proof is
to be pulled, is positioned in the holder or
holders A upon the bed 12, the press may be
15 allowed to function normally as above de-
scribed, or if it be unnecessary to secure the
proper inking of the printing cylinder, to
have the cylinder move for the full length of
the plate, the motor 49 may be controlled by
20 the manual actuation of the rod 53, to limit
such movement to that required, the lowering
of the cylinder being a manual operation
when the carriage, in its movement, does not
approach the end of the bed 12 adjacent the
25 bumper 73.

The various ink impressions transferred
to the blanket 17 of the printing cylinder
16, will be contained within a certain definite
area, although the impressions from the dif-
30 ferent plates will each be in their distinc-
tive colors, a general color effect being se-
cured which is the result of the distinct ad-
jacent colors of the different inks used and
not a secondary color effect resulting from
35 the blending of the inks of different colors
used in the imprint as in ordinary multi-
color work, although a blended effect may
be secured in some parts of the design as
when chromatic effects are desired.

By using the racks 33-34 and the gear
wheels 35-36 meshing therewith, and by
positioning the holders A upon the bed 12
with their centers spaced apart a distance
equal to the periphery of the printing cylin-
40 der 16 and its blanket 17, absolute accuracy
of register may be secured, so long as each
plate is accurately centered in relation to its
holder. A single inked impression of the
complete composite design of the four plates,
45 when four plates are used, appears upon the
blanket 17, it being essential that the plates
in each of the holders A shall be accurately
centered in relation to its holder in order to
secure precise register and the desired ac-
50 curacy in the positioning of the lines of the
different plates.

When I have referred to the absence of a
necessity for absolute precision in the cut-
ting of the racks 33 and 34 and the gears 125
35 and 36, reference was had to the depth of
the teeth and the clearances of these parts,
since in other respects reasonable precision
is required, although any lack of precision
may be corrected by adjustment of the plates
130

in their holders. By supporting the cylinder 16 upon tracks 14 and 15 by means of the circular end plates 18 and 19 during the inking and impression interval of the printing cylinder, the desired inking and printing relation of the cylinder to the various plates and the impression platen is controlled entirely independently of said racks and gears, although it is apparent that such tracks may serve merely to define the low position of the cylinder, and need not be engaged by said end plates.

Since a worm gear construction will effectively lock the worm gear against movement except under the control of the worm, the clutch mechanism 40 is used to permit the separation of the worm gear from the shaft 21 so as to permit power to be applied to the gears 35-36 through the medium of the gear 59 and the intermediate gears 57 and 58, the hand crank 60 being used to turn said gear 59. This, however, is a mere emergency provision, said hand crank being ordinarily removed from the machine so as to not interfere with the operator in the handling of the lever 68.

The rollers 38 engage the top of the channel 37 and prevent lifting of the carriage 30 as a result of the engagement of the printing cylinder with the various plates.

The springs 22 and the blocks 28 acted upon by the set screw 32 is a well known expedient, to permit adjustment of the bearings for the printing cylinder 16 to develop the desired pressure in inking the blanket 17 and making the imprint therefrom.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:—

1. A proof press for multicolor work embodying therein a bed having a sequence of plate holders adapted to receive printing plates, an impression platen, a reciprocatory carriage, a printing cylinder having a planographic offset printing surface thereon mounted upon said carriage, means simultaneously imparting definite positive rotative movement to said cylinder, and lineal traverse to said carriage, whereby said cylinder is brought successively into the operative relation to the plates upon each of said plate holders, and said impression platen, and means whereby said cylinder may be so set as to operatively engage plates upon said bed, and said impression platen, or to be held out of engaging relation therewith, said plate holders being so positioned with relation to each other, and said printing cylinder being of a diameter, to cause

the design upon the different plates to be impressed in ink in registering relation upon said cylinder.

2. A proof press for multicolor work embodying therein a bed having a sequence of plate holders adapted to receive printing plates, an impression platen, a reciprocatory carriage, a printing cylinder having a planographic offset printing surface thereon mounted upon said carriage, means simultaneously imparting definite positive rotative movement to said cylinder, and lineal traverse to said carriage, whereby said cylinder is brought successively into the operative relation to the plates upon each of said plate holders, and said impression platen, means whereby said cylinder may be so set as to operatively engage plates upon said bed, and said impression platen, or to be held out of engaging relation therewith, said plate holders being so positioned with relation to each other, and said printing cylinder being of a diameter to cause the design upon the different plates to be impressed in ink in registering relation upon said cylinder, automatically acting means operative upon the means for setting said cylinder, whereby said cylinder is normally disengaged from said plates and said platen during its reciprocatory movement in one direction, and is engaged therewith during its reciprocatory movement in the opposite direction, and manually operative means whereby said means may be set independently of said automatically acting means.

3. A proof press for multicolor work embodying therein a bed having a sequence of plate holders adapted to receive printing plates, an impression platen, a carriage adapted to receive reciprocatory movement longitudinally of said bed, a printing cylinder having a planographic offset printing surface rotatably mounted in said carriage, means carried by said carriage and operative upon said cylinder, whereby said cylinder may be moved into or out of the engaging relation to plates upon said holders and said platen, means whereby said carriage is moved lineally and said cylinder is simultaneously rotated, a source of power operative upon said means, a controller for said power, co-operating members carried by said carriage and operative upon said controller whereby the engagement of said members will actuate said controller to automatically cause a reversal of the direction of movement of said carriage, means adjacent one end of the bed co-operating with the means carried by said carriage for moving said cylinder into or out of the operative relation to the plates upon the holders whereby, toward the limit of the movement of said carriage in one direction, said cylinder will be moved in one direction with relation to said plates, and manually opera-

tive means whereby said cylinder may be moved in the opposite direction, said plate holders being so positioned with relation to each other, and said printing cylinder being of a diameter, to cause the design upon the plates upon the different plate holders to be impressed in ink in registering relation upon said cylinder.

4. A proof press for multicolor work embodying therein a bed having a sequence of plate holders adapted to receive printing plates, and an impression platen thereon, racks along the opposite edges of said bed, a reciprocating carriage, a printing cylinder having a planographic offset printing surface thereon, mounted upon said carriage, means simultaneously imparting definite positive rotative movement to said cylinder, and lineal traverse to said carriage, whereby said cylinder is brought successively into the operative relation to each of said plate holders and said impression platen, gears carried by said cylinder and meshing with said racks respectively, circular end plates upon said cylinder adapted by engagement with said tracks, to limit the downward movement of said cylinder, speed reducing gearing operative to rotate said cylinder and said gears, whereby longitudinal movement is imparted to said carriage and simultaneous positive rotative movement is imparted to said cylinder, said plate holders being so positioned with relation to each other, and said printing cylinder being of a diameter, to cause the design upon the different plates to be impressed in ink in registering relation upon said cylinder and means whereby said cylinder may be so set as to operatively engage plates upon said bed, and said impression platen, or to be held out of engaging relation therewith.

5. A proof press for multicolor work embodying therein a bed having a sequence of plate holders adapted to receive printing plates, and an impression platen thereon, racks along the opposite edges of said bed, a printing cylinder having a planographic offset printing surface thereon, and adapted to be brought successively into the operative relation to each of said plate holders and said impression platen, gears carried by said cylinder and meshing with said racks respectively, a longitudinally movable carriage in which said printing cylinder is rotatably mounted, and speed reducing gearing operative to rotate said cylinder and said gears, consisting of a rotatable shaft extending longitudinally of the press, a worm slidably mounted thereon, and a worm gear meshing with said worm and operatively connected with said cylinder, whereby longitudinal movement is imparted to said carriage and simultaneous positive rotative movement is imparted to said cylinder, said plate holders being so positioned with relation to each other, and said printing cylinder being of a diameter, to cause the design upon the dif-

ferent plates to be impressed in ink in registering relation upon said cylinder.

6. A proof press for multicolor work embodying therein a bed having a sequence of plate holders adapted to receive printing plates, and an impression platen thereon, racks along the opposite edges of said bed, tracks adjacent said racks respectively a reciprocating carriage, a printing cylinder having a planographic offset printing surface thereon, mounted upon said carriage, means simultaneously imparting definite positive rotative movement to said cylinder, and lineal traverse to said carriage, whereby said cylinder is brought successively into the operative relation to each of said plate holders and said impression platen, gears carried by said cylinder and meshing with said racks respectively, circular end plates upon said cylinder adapted by engagement with said tracks, to limit the downward movement of said cylinder, speed reducing gearing operative to rotate said cylinder and said gears, whereby longitudinal movement is imparted to said carriage and simultaneous positive rotative movement is imparted to said cylinder, said plate holders being so positioned with relation to each other, and said printing cylinder being of a diameter, to cause the design upon the different plates to be impressed in ink in registering relation upon said cylinder and means whereby said cylinder may be so set as to operatively engage plates upon said bed and said impression platen, or to be held out of engaging relation therewith.

7. A proof press for multicolor work embodying therein a bed having a sequence of plate holders adapted to receive printing plates, and an impression platen thereon, racks along the opposite edges of said bed, tracks adjacent said racks respectively, a printing cylinder having a planographic offset printing surface thereon, and adapted to be brought successively into the operative relation to each of said plate holders and said impression platen, gears carried by said cylinder and meshing with said racks respectively, circular end plates upon said cylinder adapted by engagement with said tracks, to limit the downward movement of said cylinder, a longitudinally movable carriage in which said printing cylinder is rotatably mounted, and speed reducing gearing operative to rotate said cylinder and said gears, consisting of a rotatable shaft extending longitudinally of the press, a worm slidably mounted thereon, and a worm gear meshing with said worm and operatively connected with said cylinder, whereby longitudinal movement is imparted to said carriage and simultaneous positive rotative movement is imparted to said cylinder, said plate holders being so positioned with rela-

tion to each other, and said printing cylinder being of a diameter, to cause the design upon the different plates to be impressed in ink in registering relation upon said cylinder.

8. A proof press for multicolor work embodying therein a bed having a sequence of plate holders adapted to receive printing plates, an impression platen, a carriage 10 adapted to receive reciprocatory movement longitudinally of said bed, a printing cylinder having a planographic offset printing surface rotatably mounted in said carriage, means carried by said carriage and operative 15 upon said cylinder, whereby said cylinder may be moved into or out of the engaging relation to plates upon said holders and said platen, consisting of eccentric bushings in which said cylinder is mounted, a crank 20 shaft having a crank arm adjacent each of said bushings, links connecting each crank arm with a bushing, an operating handle upon said shaft, a gear carried by said shaft, a crank fitting carried by said carriage, one 25 crank of which has a segmental gear in mesh with the gear upon said shaft, a spring-pressed slide carried by said carriage, a tap- 30 pet thereon in operative relation to the other crank of said fitting, and a bumper at one end of said bed in position to be engaged by said slide, means whereby said carriage is moved linearly and said cylinder is simultane- 35 ously rotated, a source of power operative upon said means, a controller for said power, cooperating members carried by 40 said carriage and operative upon said controller whereby the engagement of said mem- 45 bers will actuate said controller to automatically cause a reversal of the direction 50 of movement of said carriage, means adjacent one end of the bed co-operating with the means carried by said carriage for moving said cylinder into or out of the operative 55 relation to the plates upon the holders 60 whereby, toward the limit of the movement of said carriage in one direction, said cylinder will be moved in one direction with relation to said plates, and manually opera- 65 tive means whereby said cylinder may be moved in the opposite direction, said plate 70 holders being so positioned with relation to each other, and said printing cylinder being of a diameter, to cause the design upon the plates upon the different plate holders to be 75 impressed in ink in registering relation upon said cylinder.

9. A proof press for multicolor work embodying therein a bed having a sequence of plate holders adapted to receive printing 80 plates, and an impression platen thereon, racks along the opposite edges of said bed, a printing cylinder having a planographic offset printing surface thereon, and adapted 85 to be brought successively into the operative 90 relation to each of said plate holders and

said impression platen, gears carried by said cylinder and meshing with said racks re- 95 spectively, a longitudinally movable carriage in which said printing cylinder is rotatably mounted, speed reducing gearing operative 100 to rotate said cylinder and said gears, con- 105 sisting of a rotatable shaft extending longitudinally of the press, a worm slidably mounted thereon, and a worm gear meshing with said worm and operatively connected 110 with said cylinder, whereby longitudinal movement is imparted to said carriage and simultaneous positive rotative movement is imparted to said cylinder, said plate holders being so positioned with relation to each 115 other, and said printing cylinder being of a diameter, to cause the design upon the different plates to be impressed in ink in reg- 120 istering relation upon said cylinder, means whereby said worm gear may be disconnected from said cylinder, and manually opera- 125 tive means whereby said cylinder may be turned independently of said worm gear.

10. A proof press for multicolor work embodying therein a bed having a sequence of 130 plate holders adapted to receive printing plates, each of said plate holders including therein a plurality of rectangularly disposed pairs of clamps adapted to engage a plate and means whereby the clamps of each pair may be rectilinearly adjusted to accurately position the plates on one holder in relation to the plates upon other holders for the purpose of securing accurate register, an impression platen, a reciprocatory carriage, a printing cylinder having a planographic offset printing surface thereon, mounted upon said carriage, means simultaneously imparting definite positive rotative movement to said cylinder, and linear traverse to 135 said carriage, whereby said cylinder is brought successively into the operative relation to the plates upon each of said plate holders, and said impression platen, and means whereby said cylinder may be so set 140 as to operatively engage plates upon said bed, and said impression platen, or to be held out of engaging relation therewith, said plate holders being so positioned with 145 relation to each other, and said printing cylinder being of a diameter, to cause the design upon the different plates to be impressed in ink in registering relation upon said cylinder.

11. A proof press for multicolor work embodying therein a bed having a sequence of plate holders adapted to receive printing 150 plates, each of said holders including a mem- 155 ber having a circular opening therein, par- 160 allel raised tracks adjacent opposite edges thereof for guiding an inking roller, a fit- 165 ting mounted in said circular opening and adapted to engage a plate, whereby said member and said fitting may have relative- 170 ly circular movement about the axis of the 175

- opening in said member, to permit any desired degree of obliquity of the tracks upon said member with relation to the center line of said bed, and means whereby said parts may be locked against such circular movement, an impression platen, a printing cylinder having a planographic offset printing surface thereon and adapted to be brought successively into the operative relation to the plates upon each of said plate holders, and said impression platen, and means whereby definite positive rotative movement is imparted to said cylinder, said plate holders being so positioned with relation to each other, and said printing cylinder being of a diameter, to cause the design upon the different plates to be impressed in ink in registering relation upon said cylinder.
12. A proof press for multicolor work embodying therein a bed having a sequence of plate holders adapted to receive printing plates, each of said plate holders including therein a plurality of rectangularly disposed pairs of clamps adapted to engage a plate, means whereby the clamps of each pair may be rectilineally adjusted to accurately position the plates on one holder in relation to the plates upon other holders for the purpose of securing accurate register, a member having a circular opening therein, parallel raised tracks adjacent opposite edges thereof for guiding an inking roller, a fitting, operative upon said clamps, mounted in said circular opening, whereby said member and said fitting may have relatively circular movement about the axis of the opening in said member, to permit any desired degree of obliquity of the tracks upon said member with relation to the center line of said bed, and means whereby said parts may be locked against such circular movement, an impression platen, a printing cylinder having a planographic offset printing surface thereon and adapted to be brought successively into the operative relation to the plate upon each of said plate holders, and said impression platen, and means whereby definite positive rotative movement is imparted to said cylinder, said plate holders being so positioned with relation to each other, and said printing cylinder being of a diameter, to cause the design upon the different plates to be impressed in ink in registering relation upon said cylinder.
13. A proof press for multicolor work embodying therein a bed having a sequence of plate holders adapted to receive printing plates, an impression platen, a carriage adapted to receive reciprocatory movement longitudinally of said bed, a printing cylinder having a planographic offset printing surface rotatably mounted in said carriage, means carried by said carriage and operative upon said cylinder, whereby said cylinder may be moved into or out of the engaging relation to plates upon said holders and said platen, means whereby said carriage is moved linearly and said cylinder is simultaneously rotated, a source of power operative upon said means, a controller for said power, a rod operatively connected with said controller extending for substantially the entire length of said bed upon one side thereof, a fork upon said carriage straddling said rod, collars adjustably mounted upon said rod upon opposite sides of said fork, whereby the engagement of said fork with one of said collars will actuate said controller to automatically cause a reversal of the direction of movement of said carriage, and the engagement of said fork with the other of said collars will actuate said controller to interrupt the power for moving the carriage, means adjacent one end of the bed co-operating with the means carried by said carriage for moving said cylinder into or out of the operative relation to the plates upon the holders whereby, toward the limit of the movement of said carriage in one direction, said cylinder will be moved in one direction with relation to said plates, and manually operative means whereby said cylinder may be moved in the opposite direction, said plate holders being so positioned with relation to each other, and said printing cylinder being of a diameter, to cause the design upon the plates upon the different plate holders to be impressed in ink in registering relation upon said cylinder.
14. A proof press for multicolor work embodying therein a bed having a sequence of plate holders adapted to receive printing plates, and an impression platen thereon, racks along the opposite edges of said bed, a printing cylinder having a planographic offset printing surface thereon, and adapted to be brought successively into the operative relation to each of said plate holders and said impression platen, gears carried by said cylinder and meshing with said racks respectively, a longitudinally movable carriage in which said printing cylinder is rotatably mounted, and speed reducing gearing operative to rotate said cylinder and said gears, consisting of a rotatable shaft extending longitudinally of the press, a worm slidably mounted thereon, a movable support normally engaging said rotatable shaft intermediate its bearings and arranged in the path of movement of said worm, whereby said support will be displaced by said worm in travelling along said shaft, but will support the shaft against sagging when not engaged by said worm, and a worm gear meshing with said worm and operatively connected with said cylinder, whereby longitudinal movement is imparted to said carriage.

and simultaneous positive rotative movement is imparted to said cylinder, said plate holders being so positioned with relation to each other, and said printing cylinder being 6 of a diameter, to cause the design upon the different plates to be impressed in ink in registering relation upon said cylinder.

15. A proof press for multicolor work embodying therein a bed having a sequence of 10 plate holders adapted to receive printing plates, a reciprocatory carriage, a printing couple consisting of an impression surface occupying a fixed position with relation to said bed, and a printing cylinder mounted 15 upon said carriage and having a planographic offset printing surface thereon, means simultaneously imparting definite positive rotative movement to said cylinder, and lineal traverse to said carriage, whereby 20 said cylinder is brought successively into the operative relation to the plates upon each of said plate holders, and said impression surface, and means whereby said cylinder may be so set as to operatively engage plates 25 upon said bed, and said impression platen, or to be held out of engaging relation therewith, said plate holders being so positioned with relation to each other, and said printing cylinder being of a diameter, to cause 30 the design upon the different plates to be impressed in ink in registering relation upon said cylinder.

16. A proof press for multicolor work embodying therein a bed having a sequence of 35 plate holders adapted to receive printing plates, an impression platen, a carriage adapted to receive reciprocatory movement

longitudinally of said bed, a printing cylinder having a planographic offset printing surface rotatably mounted in said carriage, 40 means carried by said carriage and operative upon said cylinder, whereby said cylinder may be moved into or out of the engaging relation to plates upon said holders and said platen, means whereby said carriage is moved lineally and said cylinder is simultaneously rotated, a source of power operative upon said means, a controller for said power, a rod operatively connected with said controller extending for substantially 45 the entire length of said bed upon one side thereof, a fork upon said carriage straddling said rod, collars adjustably mounted upon said rod upon opposite sides of said fork, whereby the engagement of said fork with 50 one of said collars will actuate said controller to automatically cause a reversal of the direction of movement of said carriage, and the engagement of said fork with the other of said collars will actuate said controller to interrupt the power for moving 55 the carriage, and means whereby said cylinder may be moved into and out of engaging relation with the plates upon said holders and said platen, said plate holders being so positioned with relation to each other and said printing cylinder being of a diameter, to cause 60 the design upon the plates upon the different plate holders to be impressed in ink in registering relation upon said cylinder.

In witness whereof I have hereunto affixed my signature, this 24th day of January, 1923.

FRANK C. MARQUARDT.
